UNITED STATES PATENT OFFICE.

OLE O. MALAND, OF ST. HILAIRE, MINNESOTA.

PUMP.

1,176,387.

Specification of Letters Patent.

Patented Mar. 21, 1916.

Application filed May 27, 1915. Serial No. 30,791.

To all whom it may concern:

Be it known that I, OLE O. MALAND, a citizen of the United States, residing at St. Hilaire, in the county of Pennington and State of Minnesota, have invented a new and useful Pump, of which the following is a specification.

The device forming the subject matter of this application is a pump, the invention 10 aiming to provide a novel driving mechanism for the plunger portion of the pump.

It is within the scope of the invention to provide novel means whereby the plunger portion of the pump may be made to operate 15 without jar.

The invention aims to improve generally and to enhance the utility of structures of that type disclosed.

With the above and other objects in view 20 which will appear as the description proceeds, the invention resides in the combination and arrangement of parts and in the details of construction hereinafter described and claimed, it being understood that 25 changes in the precise embodiment of the invention herein disclosed can be made within the scope of what is claimed, without departing from the spirit of the invention.

In the accompanying drawings:—Figure 30 1 shows the invention in elevation; Fig. 2 is an elevation wherein the device is viewed at right angles to the showing of Fig. 1; Fig. 3 is a cross section of the water wheel; Fig. 4 is a sectional elevation showing one 35 form of shifting mechanism whereby one of the pinions in the gear train may be moved.

In carrying out the present invention there is provided a base 1 carrying a standard 2. Mounted on the base 1 is a bearing 40 frame 3 terminated in an upwardly prolonged extension 4. Disposed parallel to the extension 4 of the frame 3 is a standard 5 which is carried by the base 1, the standard 5 if desired being connected by a brace 6 to 45 the base 1. Mounted upon the base 1 or otherwise supported is a pump 7 which may be of any desired construction.

The invention includes a water wheel denoted generally by the numeral 8, the same 50 comprising heads 9 united by a tubular hub 10. Rim bands 11 circumscribe the heads 9 and extend inwardly beyond the inner or adjacent faces of the heads. Extended between the rim bands 11 and the hub 10 are 55 curvilinear buckets 12. A shaft 14 lies within the tubular hub 10 and is secured

thereto in any desired manner as shown at 15. The shaft 14 is journaled in the standard 2 and the frame 3. Water may be supplied to the wheel 8 in any desired manner. 60 As shown the supply for the wheel 8 comprises a flume 16 upheld by a support 17 in the base 1, the water being carried away by a tail race 18 upheld by the base 1. One end of the shaft 14 extends between the 65 frame 3 and the standard 5 and to this end of the shaft is secured a gear wheel 19 meshing into a pinion 20 secured to a shaft 21 journaled in the frame 3 and in the standard 5. Secured to the shaft 21 is a gear wheel 70 22 meshing into a pinion 23 carried by a shaft 24 journaled in the extension 4 of the frame 3 and in the standard 5. The shaft 24 carries a gear wheel 25 meshing into a pinion 26 carried by a shaft 27. The shaft 75 27 is journaled in the extension 4 of the frame 3 and in the standard 5. The pinion 26 is operatively connected with the shaft 27 by means of a spline 29, the construction being such that although the pinion may 80 slide longitudinally of the shaft, an operative, rotary connection exists between these parts.

Any suitable means may be provided for shifting the pinion 26 on the shaft 27 to 85 move the pinion in and out of mesh with the gear wheel 25. As disclosed best in Fig. 4, the hub 28 of the pinion 26 may be provided with a circumscribing groove 30 receiving projections 31 on a shifting collar 32 connected with a ring 33 by means of a spider 34, the ring 33 being mounted to reciprocate on the shaft 27. An actuating member for the collar 32 is provided, the actuating member being in the form of a U-shaped element 90 comprising arms 35 mounted to slide in the extension 4, the inner ends of the arms being connected with the ring 33, and the outer ends of the arms merging into a handle 36.

Secured to one end of the shaft 27 is a 100 crank disk 37 carrying a wrist pin 38 receiving pivotally the lower end of an upwardly extended pitman 39, the upper end of which is adjustably pivoted as shown at 40 to one end of a transverse head 41 secured to the 105 upper end of a pendulum rod 42 carried by a shaft 43 which in its turn is upheld in the standard 5 and the extension 4 of the frame 3. The pendulum rod 42 may be secured to the shaft 43 and the shaft 43 may rock, or 110 the shaft 43 may be fixed, the pendulum rod swinging on the shaft—all as will be under-

stood clearly by a mechanic having before him the present disclosure. Mounted for adjustment longitudinally of the pendulum rod 42 is a weight 47 held in place by a set 5 screw 48. One end of the head 41 of the pendulum 42 is offset as shown at 44 and pivoted thereto as shown at 45 is the upper end of a plunger 46 constituting a part of the pump 7.

- 10 A shaft 49 is journaled for rotation in the standard 2 and in a casing 50 carried by the standard, one end of the shaft 49 being squared as shown at 51 to receive a wrench or key. Secured to the shaft 49 is a drum 52 about which is trained a flexible element 53 carrying a weight 54. Secured to the shaft 49 within the contour of the casing 50 is a pulley 55. A pulley 56 is secured to the shaft 14 of the water wheel 8 and about the 15 pulleys 55 and 56 is trained a belt 57 which may be used for elevating the weight 54. One end of the water wheel 8 carries a ratchet wheel 58 adapted to be engaged by a pawl 59 secured to the pulley 56.
- 20 The function of the shaft 49 and parts operatively connected therewith is to impart an initial rotation to the water wheel, thereby facilitating the starting of the device. The weight 54 actuates the flexible element 25 53, the same rotating the shaft 49 through the instrumentality of the drum 52. When the shaft 49 is rotated, the pulley 55 on the shaft 49 will actuate the belt 57, the latter rotating the pulley 56 which is loose on the 30 shaft 14. The pawl 59 on the pulley 56 co-acts with the ratchet wheel 58 on the water wheel 8 and rotates the water wheel.

When the water wheel is rotated by water delivered thereon by means of the flume 16 40 or otherwise the pawl 59 will click over the ratchet wheel 58, as will be obvious from Fig. 1. When the water wheel 8 is rotated, motion will be transmitted to the pump plunger 46 by a gear train comprising the 45 shaft 14, the gear wheel 19, the pinion 20, the shaft 21, the gear wheel 22, the pinion 23, the shaft 24, the gear wheel 25, the pinion 26, the shaft 27, the crank disk 37, the pitman 39 and the pendulum 42. The 50 weight 47 may be shifted longitudinally of the pendulum rod 42 to vary the moment of

the weight and consequently to affect the speed of reciprocation of the plunger 46.

The plunger 46 may be placed out of gear at any time by moving the pinion 26 laterally so that the same does not mesh into the gear wheel 25, this operation being carried out through the instrumentality of the actuating member 36—35, the ring 33, the spider 34, the shifting collar 32, its projections 31 and the grooved hub 28 of the pinion 26.

By means of the gear train comprising the various pinions above described, a rapid reciprocation will be imparted to the plunger 46 of the pump, the pendulum 42 acting as an equalizing or stabilizing device. The weight 54 and parts co-operating therewith constitute a yieldably actuated means for imparting an initial rotation to the water 70 wheel 8.

Having thus described the invention, what is claimed is:—

In a device of the class described, a supporting structure; a pendulum including a 75 transverse head and a depending stem, the head being fulcrumed intermediate its ends on the supporting structure; a weight adjustable along the stem; means for holding the weight in adjusted positions on the stem; 80 a pump including a plunger pivoted to one end of the head; a gear train carried by the supporting structure and including a crank; a pitman connecting the crank with the other end of the head; a clutch interposed in 85 the gear train; a water wheel operatively connected with the gear train; upper and lower pulleys; means for supporting the pulleys for rotation; a continuous belt engaged around the pulleys; pawl and ratchet 90 mechanism connecting the lower pulley with the water wheel; and yieldably actuated means for imparting a rotation to the upper pulley.

In testimony that I claim the foregoing 95 as my own, I have hereto affixed my signature in the presence of two witnesses.
